UNITED STATES PATENT OFFICE.

ROBERT J. McNITT, OF PERTH AMBOY, NEW JERSEY.

ELECTROLYZING FUSED BATHS.

Application filed February 2, 1921, Serial No. 441,921. Renewed April 4, 1924.

To all whom it may concern:

Be it known that I, ROBERT J. McNITT, a citizen of the United States, residing at Perth Amboy, in the county of Middlesex and State of New Jersey, have invented certain new and useful Improvements in Electrolyzing Fused Baths, of which the following is a specification.

My invention pertains to electrochemical processes operating with fused electrolytes, and has for its purpose the elimination or reduction of imperfections existing in such processes. Among these imperfections may be mentioned the following:

1st. The application of heat from external sources is not advantageously made, and in attempting to maintain thermal equilibrium by means of the electrolytic current there occur excessive energy losses, and those conditions favorable to high yields (current density and electrode spacing) are sacrificed. Where units are operated electrically in series as is customary, the current is adjusted to maintain a favorable temperature in the coldest unit, that is the unit operating with highest energy efficiency; and in order to prevent excessive temperature in other units, it is customary, to shunt a portion of the current around these units through an external resistance, to disconnect the hot units from the circuit from time to time, to change the electrode spacing, to circulate cooling fluids through ducts in the electrolyte or furnace walls, or to vary the rate of heat radiation from external surfaces. These methods of control result in loss of power, loss of production, unfavorable conditions for high average yields, and high costs for attendance and maintenance.

2nd. In the operation of units connected electrically in multiple, it is difficult to maintain proper division of the electric current, on account of the temperature resistance characteristic of the fused electrolyte. After the current has been carefully adjusted, owing to a slight change in radiation constant or operating efficiency one unit may tend to chill off with consequent increase in the electrolyte resistance and a diversion of current to other units. One or more of these other units will warm up under the additional current with corresponding reduction in the resistance of their electrolytes. Hence more and more of the

current will be diverted from the cold unit and it will tend to freeze up. Some of the units may also operate at lower efficiency with rising temperature, and with the increased energy losses a rapid accumulative 60 temperature effect occurs, with more and more diversion of current.

In processes using pencil anodes in multiple and a common molten cathode, this difficulty is in some measure overcome by 65 the relatively high resistance of the anode pencils and by making frequent adjustments in the distance between anode and cathode; but in processes using fixed electrodes, or electrodes with larger surfaces and low re- 70 sistance it has been considered impracticable to operate more than one electrochemical unit in a single cell, or to operate individual cells in multiple except in a multiple series arrangement, where a sufficient 75 number of units are in series, so that the average resistance characteristics of all parallel branches shall be approximately the same.

3rd. The electrolyte is not maintained in 80 such condition as to uniformity of constituents, temperature and purity as is necessary to insure uniformly high ampere yields. It is customary to allow impurities to accumulate until the yield falls below 85 the economic limit, whereupon the electrolyte is removed, and the cell cleaned and re-filled with fresh electrolyte; a method of operation which is costly in both labor and materials, and which results in relatively 90 low average yields. Also, due to the tendency to accumulation of impurities, all materials put into the bath must be as pure as possible. Where mixed baths or fluxing agents are used it is difficult to maintain 95 in all units the most favorable mixtures of constituents. Generally it is necessary to make frequent analyses of the bath in each unit, and, treating each unit separately, to add such amounts of the various materials 100 as are determined to be necessary.

4th. On account of structural limitations and operating difficulties the size of the individual unit used in these processes is small, and the energy lost through radiation and conduction is great in comparison with the energy consumed in useful work. Also the cost of operating and maintaining numerous small units is high.

Now the improvement which I have made 110

reduces or eliminates these imperfections and consists in its preferred embodiment:

In causing the fused electrolyte of proper constitution, temperature, and purity to flow to each electrochemical unit, in excess of the amount required for electrolytic decomposition; controlling the temperature of the electrolyte in the unit at the desired point by regulating the temperature and rate of flow of the entering electrolyte; circulating the electrolyte through the unit in such a manner that impurities are taken up by the residual portion of the electrolyte (the part not decomposed) and removed with such portion from the zone of electrolytic action; collecting said residual electrolyte, laden with impurities, in a place outside the zone of electrolytic action, and submitting same to purification, replenishment, the application of heat, cold, or such additional treatment as may be necessary to produce an electrolyte of proper constitution, temperature and purity; and causing the latter to again flow in excess to each unit as described before.

By way of illustration I shall describe my invention as applied to a process of electrolyzing fused sodium chloride in units consisting of vertical electrodes separated by a porous partition or diaphragm, and for assistance to a clear understanding of the invention reference is made to the accompanying drawings, in which the figures are diagrammatic in character and wherein:

Fig. 1 is a vertical longitudinal view, partly in section along line 1—1 of Fig. 2, of a typical installation for the above purposes.

Fig. 2 is a plan view of the same;

Fig. 3 is a partly sectional view along the central line 3—3 of Fig. 2;

Fig. 4 is a transverse vertical section on line 4—4 of Fig. 2;

Fig. 5 is a transverse vertical section on a somewhat larger scale of one of the electrolyzing units; and

Fig. 6 is a longitudinal vertical section on a somewhat enlarged scale of one of the electrolyzing units.

The illustrated installation comprises a multiplicity of electrolyzing units 10 arranged in multiple electrical connection with a source of current 11, and are grouped together to reduce the external heat radiating and conducting surfaces. The walls of the cells 12 in which the units are located are preferably constructed of refractory brick and fireclay shapes and are preferably surrounded by thermal insulating material, as for example bricks 13 made from kieselguhr.

The anodes 14 which form part of the cell wall are made of graphite and are respectively connected with the source of electrical energy 11 through graphite con-

ductors 15. The cathodes 16 may be of copper and as shown each comprises a frame of substantially the same height as the anode and supported through a spider, perforated plate or the like 17 by a copper conductor rod 18. The conductor rods are joined in multiple electrical connection by the conductors 19 with the source of current 11.

The diaphragms 20 may comprise rectangular bodies of wire gauze supported by hoods 21 surmounting the cathodes. In turn these hoods are supported by pipes 22 through which the metallic sodium which collects in the hoods in operation may be withdrawn. Inwardly extending collars 21' centrally of the hood provide passages between the upper and lower levels of the cells.

The chlorin gas developed in the electrolysis is removed through pipes 23.

The bottoms 24 of the cells converge as shown and open into a duct or trough 25 running lengthwise of the installation, there being shown one of these ducts for each of the two rows of cells. Each duct 25 opens at one end thereof into an electrolyte reservoir 26 and the two reservoirs 26 are in communication at or near their bottoms through a cross-passage 27 (Fig. 4). In each reservoir 26 a pump 28 is provided, the outlet passage whereof leads to respective filter chambers 29. Each filter 29 has an outlet pipe 30 communicating with a central reservoir 31.

A suitable pump 32 in reservoir 31 has its inlet side open to the electrolyte in the reservoir while its outlet connects through pipe 33 with a cell-supply duct or manifold 34 which lies in a channel in the top of the brickwork between and above the two rows of cells. Branch pipes 35 distribute the electrolyte to the individual cells, regulation of the flow through the respective branch pipes being effected by means of the valves 36. The electrolyte is preferably introduced into the cell at two points on each side thereof, a portion entering at the top of the anode 14 through pipes 37 (Fig. 6) and a portion entering near the top of the bath through the pipes 38. The relative flow through pipes 37 and 38 is adjusted by suitable devices, not shown, such as deflectors in the branch pipes 35.

For supplying additional heat to the electrolyte flowing to the units, each of the individual feed pipes 37 may be provided with an electrical resistor 39. For the purpose of extracting heat from the electrolyte as it passes through the branch ducts, the latter are provided at their upper portions with suitable water-jackets 40 (Fig. 5).

Beyond the branch pipes of the last cells the manifold 34 makes a return bend, and extends rearwardly beneath the cell-sup-

plying portion of the same, through the central reservoir 31 and into an electrolyte-heating retort 41. The heating means for this retort may be a gas or an oil burner, indicated at 42. Through a valved outlet 43 the electrolyte which is not diverted to the cells 10 is returned to the reservoir 31 for recirculation, valve 44 in the section of the manifold extending into the retort 41 being partly or entirely closed. If substantial reheating of the electrolyte is necessary, valve 44 is opened and valve 43 is partly or entirely closed.

Arranged near the reservoirs 26 and communicating respectively therewith are retorts 45 into which the solid replenishing materials, for example common salt with small quantities of fluxing agents, are introduced through hoppers 46, and in which such materials are fused and purified. The retorts may be externally heated by means of gas or oil burners 47. For purifying the materials, the latter in a fused state are passed through special low-voltage electrochemical units 48, shown submerged in the fused baths in retorts 45, and provided with insoluble or removable anodes. The fused replenishing materials are discharged from units 48 through pipes 49 into reservoirs 26 where they mingle with the residual portion of the electrolyte therein, and are filtered with the latter.

For maintaining an elevated temperature in the fused electrolyte in the reservoirs 26, an electrical resistor 50 may be located along the bottoms thereof and the bottom of the cross duct 27 which connects the reservoirs 26. The terminals of the resistor are indicated at 51. Similarly, the duct 25 may be provided with an electrical resistor 52 for maintaining the fused electrolyte therein at an elevated temperature.

In using the apparatus described for carrying out my process, a fused electrolyte of proper temperature, purity and constitution, for example sodium chlorid and such fluxing agents as may be preferred, is pumped from reservoir 31 through the manifold 34 to each unit, in excess of the amount required for electrolytic decomposition. The flow of the electrolyte to the various units 10 is regulated by the valves 36 in the branch ducts 35, and the temperature of the entering electrolyte is regulated by means of the respective electric heating elements 39 (Fig. 5). By this regulation the temperature of the electrolyte undergoing electrolysis is held at the point favoring highest yields. Also a proper division of electric current is maintained between the various units connected in multiple.

The electrolyte is circulated through the units in such manner (see arrows in Figs. 5 and 6) that solid impurities such as par-

ticles of carbon, carbides, iron, calcium, magnesium, copper, sand and fireclay, as well as impurities in solution, such as the metallic chlorids, are taken up by the residual portion of the electrolyte (i. e. the portion not decomposed) and removed from the zone of electrolytic action. This residual portion of the electrolyte laden with impurities passes through the open bottom of each unit into one of the ducts 25 where it unites with the residual portions from the other units, and by these ducts 25 the electrolyte is conveyed to the reservoirs 26. In the latter are facilities for removing impurities from the electrolyte. Purification may consist in chemical treatment, or electrolysis in a specially designed unit, to separate out impurities from solution, or it may consist merely in settling or filtering out of the solid impurities. The detailed method of purification depends on the nature of the impurities, which in turn depends upon the purity of the materials used for replenishment, and the nature of the materials used in the construction of the supporting structure and linings of the cell surrounding the unit, as well as upon the skill of the operator. In general, mechanical treatment is sufficient and accordingly I have shown a filter 29 in each reservoir 26 through which the electrolyte is forced by the pumps 28. The filters may be constructed of wire cloth, perforated metal, coke, charcoal and similar materials. From the filters 29 the purified electrolyte passes into the central reservoir 31 for recirculation.

The facilities for fusing and mixing the materials supplied as required for replenishing the electrolyte are preferably grouped together with the units as shown, and where the number of units is sufficient there may be facilities for purifying these materials. In the example described the replenishing materials, mostly common salt with small quantities of fluxing agents are fused in the retorts 45, being fed solid thereto from the hopper 46 (Fig. 1). The purification treatment of the replenishing materials is here illustrated as effected by electrolyzing the fused material in a special low voltage unit 48, the anodes of which are insoluble or removable. By this treatment oxygen bearing impurities are broken down and prevented from entering the regular process and attacking the permanent graphite electrodes. The units 48 are shown submerged in the fused baths in retorts 45.

The fused replenishing materials are discharged from the units 48 through the conduits 49 into the reservoirs 26 where they mingle with the residual portion of the electrolyte and are filtered with the latter. The temperature of the fused electrolyte in the

reservoirs 26 is maintained at a suitable point by the generation of heat in the electrical resistors 50 and 52 located at the bottoms of the reservoirs and the ducts 25 and 27.

The purified and replenished electrolyte is discharged from the filters 29 into the reservoir 31 whence it is again pumped in excess into the various units 10 through the manifold 34. The fused electrolyte which is not diverted from the manifold to the various units flows through the return leg of the manifold to the reservoir 31 by way of cock 43 (Figs. 3 and 4). A portion or all of the electrolyte returning may be discharged through valve 44 into retort 41 (Figs. 2 and 3) where heat is added, and the hot electrolyte discharged by pipe 53 into reservoir 31 from which it is again pumped to the various units through the manifold 34.

By the addition of heat to the electrolyte in retorts 45 and 41 and the resistor in duct 27, it is possible to maintain thermal equilibrium in the system and still operate the units with a current density and electrode spacing most favorable for maximum yields. This additional heat replaces a considerable portion of the total energy losses and results in a saving in electrolytic power by reducing the operating voltage to a point as near as possible to the decomposition voltage.

Where heat is added by the combustion of fuels, retorts 45 and 41 should be made wholly or as to linings from calorized steel, nickel-chromium or other suitable alloys. As the quantity of exit gases from the retorts may be considerable and as they leave the heating surfaces at a high temperature it is economical to pass them through some form of economizer (not shown), as for example a steam boiler.

If the cost of electrical power is relatively low, heat may be obtained for fusing the replenishing materials and maintaining temperature equilibrium by applying the power directly or indirectly through resistors in retorts 45 and 41 or in the reservoirs 26 and 31.

The regulation of temperature of the electrolyte entering each unit is brought about by adding or extracting heat at some point between the control cock 36 of each unit and the point where the electrolyte enters the chamber surrounding the unit. This heat is added by applying auxiliary electric power, or by the combustion of gas or oil. In the embodiment illustrated in the drawings, it is obtained through the electrical resistors 39 (Fig. 5) in each branch duct 35 which connects each cock 36 with the chamber surrounding the unit. Where oil or gas fuel is used a small coil or re-

tort (not shown) of sufficient heating surface is inserted between each cock and the corresponding branch duct, and the entering electrolyte is made to flow through this coil or retort while flames are projected against the external surface. Heat is extracted by water-cooling. In the example illustrated, the upper portion of each branch duct 35 is surrounded by a water-jacket 40 (Fig. 5) so proportioned that the temperature of the flowing electrolyte may be reduced without risk of freezing or solidification.

By the manner of flow through manifold 34, the electrolyte enters the control cock 36 of each unit at practically the same temperature. Also the constitution of the electrolyte is practically uniform in all units. These two facts make it possible to control most units by merely regulating the rate of flow of the entering electrolyte. In units having abnormal radiation or efficiency characteristics, however, it is advantageous to be able to regulate the temperature of the entering electrolyte.

By virtue of the control obtained through regulation of the temperature and rate of flow of the entering electrolyte, it is possible to adjust the electrolytic current for average conditions and to run for a long period without readjustment. The excess heat developing in any unit tending to run warm is carried by a relatively large flow of slightly superheated electrolyte into the duct 25, where it warms up the chilled electrolyte returning from units which tend to run cold. This thermal equalizing effect is most advantageous in saving energy and in stabilizing the system, thus reducing the attendance required.

The circulation of the electrolyte through each unit should be such as to insure that the purest electrolyte shall always be present in the electrolytic zone, that impurities shall be prevented from entering the electrolytic zone and shall be removed to the reservoirs 26 with the residual electrolyte. The circulation should also facilitate the temperature control of the electrolyte of each unit. In the example described, this is accomplished by causing a portion of the electrolyte to enter at the top of the anode and a portion to enter near the top of the bath (Figs. 5 and 6). By adjusting the relative flow entering at these points, which is accomplished by suitable deflectors in the ducts 35 leading from the cocks 36 to each electrolytic chamber, and by properly proportioning the various openings and passages this method of circulation is very satisfactory.

The auxiliary electric heat is advantageously applied in the manifold 34 and in the duct 25 to facilitate starting up of the

system and to maintain it in smooth operation.

The application of my invention to the process described above carries the following improvements:

(1) A large reduction in energy losses is effected;

(2) The electrolytic power used per lb. of product is reduced;

10 (3) The current density, electrode spacing, and the condition of the electrolyte as to constituents, temperature and purity are ideal for uniform and continuous high yields;

15 (4) The units are operated entirely satisfactorily in multiple, which in turn permits them to be grouped in the compact simple system illustrated;

20 (5) The interruptions required for changing the diaphragm and for cleaning are materially reduced;

(6) The labor and attendance required in the operation are minimized;

25 (7) By continuous operation under uniform conditions there is less wear and tear, and by fusing the replenishing materials in one place and handling the molten bath mechanically both labor and energy are reduced.

30 I do not limit my invention to the arrangement and details described, as it may be applied with advantage to any arrangement of units or to a single isolated unit. The electrochemical units may be located in a common bath or separated by cell partitions.

35 Likewise the purifying and treating equipment may be contained in a common bath with the electrochemical unit or units, or may be located in a separate compartment as described above.

40 The operation of purification and treatment of the electrolyte may be divided, a part of the operation, as for example settling and filtering, being carried on in connection with the units, while special treatment is carried on continuously or in batches, in a special purification plant isolated from the units. Likewise the preparation of the replenishing materials may be carried on in connection with the units as described or may be done in a separate plant.

45 The circulation of the electrolyte may be continuous or intermittent. Each unit may have an independent circulation and purification system, or a number of units may be connected to a common system. The electrolyte may be made to flow to two or more units simultaneously or to one after the other in succession. The various units may 50 receive electrolyte from separate branches of the main duct, or the electrolyte may pass through one unit after the other in series. In the latter case the regulation of rate of flow through any unit is secured by passing

more or less of the main stream around the 65 unit through a by-pass.

Where units are in series electrical connection and receive electrolyte from a common source it may be necessary to avoid annoyance from cross currents by breaking 70 the continuity of the electrolyte stream flowing to and from the units by means of a cock with an oscillating deflecting vane, a rotating disk or screw, a duplex tilting bucket, or other appropriate device. 75

I claim:—

1. The herein-described process of electrolyzing fused baths, comprising causing a fused electrolyte to flow in excess through an electrochemical unit; controlling the operating temperature of said unit by regulating the temperature and rate of flow of the electrolyte; regenerating the undecomposed portion of the electrolyte at a point outside the zone of electrolytic action, and returning 85 the same to the electrochemical unit.

2. Process according to claim 1 in which the electrolyte is caused to flow repeatedly through a plurality of electrochemical units 90 in the same electrical circuit.

3. Process according to claim 1 in which the electrolyte is caused to flow repeatedly through a plurality of electrochemical units 95 electrically connected in multiple.

4. The herein-described process of electrolyzing fused baths, comprising grouping a plurality of electrochemical units in close proximity to each other to minimize loss of heat by radiation; causing a fused electrolyte to flow in excess through said units; collecting the excess electrolyte at a common point outside the zone of electrolytic action; supplying heat to the electrolyte at the said point; and returning the electrolyte to the 100 said units in cyclic flow. 105

5. The herein-described process of electrolyzing fused baths, comprising grouping a plurality of electrochemical units in close proximity to each other to minimize loss of heat by radiation; causing a fused electrolyte to flow in excess through said units; collecting the excess electrolyte at a common point outside the zone of electrolytic action; regenerating the electrolyte and supplying 110 heat thereto at the said point; and returning the electrolyte to the said units in cyclic flow. 115

6. The herein-described process of electrolyzing fused baths, comprising causing a fused electrolyte to flow in excess through a plurality of electrochemical units electrically connected in multiple, and separately controlling the supply of electrolyte to individual units to equalize the current conditions therein. 120

125 In testimony whereof, I affix my signature.

ROBERT J. McNITT.
